WILLIAM EVANS, OF PITTSBURG, ASSIGNOR TO JOHN EVANS, OF
PHILADELPHIA, PENNSYLVANIA.

Letters Patent No. 88,861, dated April 13, 1869.

IMPROVED EAR-BLANK FOR ELLIPTIC SPRINGS.

The Schedule referred to in these Letters Patent and making part of the same.

To all whom it may concern:

Be it known that I, WILLIAM EVANS, of Pittsburgh, in the county of Allegheny, and State of Pennsylvania, have invented a new Improvement in Carriage-Spring Heads; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view of the bar of metal, prepared for cutting therefrom the ears for spring-heads;

Figure 2, one of the spring-heads complete and ready for attachment; and in

Figure 3, the spring-head with the ear shown in red, as attached.

This invention relates to an improvement in carriage-springs, such as are formed from several layers of flat steel, and commonly known as elliptic springs, the object being to simplify the process of forming the heads.

To this end, the invention consists in first rolling a bar of metal, so as to raise thereon a rib, at a distance from the edge of the bar equal to about the thickness of the end of the spring to which the ears are attached.

This construction enables me to cut the ears both right and left with the same die, the rib serving as a guide for the position of the ear on the spring, as a means of holding the ear in position, and also as an aid in welding the ear to the spring.

In order to the clear understanding of my invention, I will fully describe the same as illustrated in the accompanying drawings.

Various devices have been resorted to to facilitate the process of forging spring-heads, and it is generally conceded that the most economical plan is to cut the ears right and left, and apply them to opposite sides of the spring, temporarily secured to the end of the spring until the whole can be heated and welded together.

Heretofore, it has required two sets of dies, one for the right-hand ear, and the other for the left. To avoid the use of the two dies, and simplify the construction of the ears for the spring, I first roll the metal into a bar, of suitable thickness, as seen in fig. 1, and, by preference, form a rib, A, near the edge,

upon one side, and a rib, B, upon the other side, near the upper edge, this rib being distant from the edge of the metal about equal to the thickness of the head of the spring to which the ears are attached. Then, in a die of the proper form for the ears, I cut from the bar, as denoted in red and blue, fig. 1, which forms the ears, the reverse of each other, or what we term right and left ears.

I also punch at a, for the rivet through the spring-head, and also perforate the spring, as at d, for convenience of attachment to the spring-head. In fig. 2 the ear is shown complete.

The end of the spring C, shown in fig. 3, is formed with a projecting stud, f, which corresponds to the perforation d in the respective ears. Then the opposite ears are placed upon the opposite sides, the stud f entering the perforations d in each, and the rib on the inside of the ear resting against the surface of the spring, the ears are temporarily held to the spring. Then the head is heated, and the parts welded together by dies prepared for the purpose in the usual manner.

Thus, by a single pair of dies, I form both ears, and with very little waste of material.

The bar from which the ears are cut may be formed with a single rib, A, and cut in the same dies, the right-hand ears being cut from the bar, one side up, and the left-hand ears from the said bar by turning the bar over, so that the rib comes upon the opposite side, the only operation which the dies have to perform being simply to shape the ears.

The rib on the ear not only facilitates the placing of the ears in position, but places the metal where it is needed, and facilitates the process of welding.

Having fully described my invention,

What I claim as new and useful, and desire to secure by Letters Patent, is—

1. Forming the ears from a bar of metal, having a rib on one or both sides thereof, substantially as and for the purpose set forth.

2. Forming the studs f on the spring, and the perforations d in the ear, as and for the purpose described.

WILLIAM EVANS.
